UNITED STATES PATENT OFFICE.

ANDRÉ JUNOD, OF NEW YORK, N. Y.

SOUND RECORDING AND REPRODUCING DEVICE.

Application filed October 3, 1921. Serial No. 504,967.

To all whom it may concern:

Be it known that I, ANDRÉ JUNOD, a citizen of the United States, and a resident of the borough of Manhattan, city of New York, in the county of New York and State of New York, have invented certain new and useful Improvements in a Sound Recording and Reproducing Device, of which the following is a specification.

10 This invention relates to an improved sound recording and reproducing device. Its object is the production of a device which with a single stylus is adapted to actuate with the vibrations of a pair of the usual diaphragms of a sound recording device, or the diaphragms of a sound reproducer are caused to vibrate with the oscillations of the stylus. The functions are performed with the same stylus whether the record to be made or the one used is provided with vertical undulations, that is to say, vertical cuts or with lateral undulations that is to say lateral cuts.

25 Another object of the invention is the production of a device by means of which the sound emanating from the trumpet thereof, is amplified in volume and the distinctness of the tone improved.

30 A specific object of the invention is to make the stylus thereof to swing in either vertical or horizontal planes.

The organization of the invention comprises a pair of diaphragms of a pair of sound boxes, that will be effective when 35 both the said diaphragms simultaneously vibrate in the same direction or when the direction of vibrations of one is opposite to the other. The stylus is supported so that when coacting with a vertical cut record it causes the diaphragms to simultaneously vibrate in the same direction, that is to say, they simultaneously move in and then both move out, the effect of one being added to the other. When the stylus coacts with a 40 lateral cut record, one diaphragm moves out while the other one is moving in, and their combined effect is a summation of both.

45 Transverse arms extend from the support of the stylus and have their outer ends connected to a pair of diaphragms, by means of which the movements of the stylus are communicated to both.

50 The invention is further characterized by the fact that the device functions for either vertically cut or laterally cut sound records

without any adjustment or change of its parts.

Fig. 1 represents a front elevation of the improved sound recording and reproducing device; Fig. 2 shows a top plan view of Fig. 1 and section of Fig. 1 on the line 2, 2; Fig. 3 is a section of Fig. 1 on the line 3, 3; Fig. 4 indicates a section of Fig. 1 on the line 4, 4 with a portion thereof in full lines; Fig. 5 shows a section of Fig. 1 on the line 5, 5; Fig. 6 indicates a section of Fig. 2 on the line 6, 6; Fig. 7 represents a side view of some modified details and Fig. 8 shows a section of Fig. 7 on the line 8, 8.

Referring to Figs. 1 to 4 inclusive a pair of sound boxes 20 and 21 are respectively indicated with the diaphragms 23 and 24. A tone arm 25 has formed therewith the cross connection 26, from which latter extend the branch tone arms 27. The latter are connected to the sound boxes 20 and 21 in the usual manner. A supporting frame 32 connects the said sound boxes and has extending therefrom the pair of horizontally disposed knife edge projections 33. A supporting and oscillating plate A is indicated with the upwardly inclined arms 35 which join at their upper ends to form the upper portion 36 and their lower ends join to form the curved portion 37. Lateral portions 38 extend from the arms 35 and have formed therein bearings 39 with sufficient clearance to enable the plate A to oscillate in a plane at right angles to the diaphragms 23 and 24. In the upper portion 36 of the plate A is formed the vertically disposed bearing 40 similar to 39, and in the curved portion 37 is formed the similar vertically disposed bearing 41. A stylus supporting bracket B is indicated with the vertical arms 46 and 47, the third arm 48 and the fourth arm 49. The arm 46 has extending therefrom the vertically disposed knife edge projection 50 and the arm 47 has extending therefrom the similar projection 51. The projection 50 is seated in the bearing 40 and the projection 51 is seated in the bearing 41. The spaces between the bearings 40, 41 and the projections 50, 51 are sufficient to enable the supporting bracket B to oscillate to and fro to planes inclined to the plane of the diaphragms 23 and 24. The end of the arm 48 is spaced from a vertical plane extending through the projections 50 and 51 to locate the stylus 64, to be described, at a sufficient

distance from the diaphragms 23 and 24 to obtain sufficient leverage to operate them.

An adjusting screw 52 with the bearing point 52^a is in threaded engagement with the fourth arm 49, and preferably a little below the plane of the projections 33 and to the rear of the plane of the diaphragms 23 and 24.

The axis of oscillation of the vertical projections 50 and 51 and the axis of oscillations of the projections 33 are substantially equally distant from the centers of the diaphragms 23 and 24. Transverse arms 53 and 54 extend from the bracket B and have their outer ends respectively fastened to the diaphragms 23 and 24. The said arms are maintained in tension by their coaction with the said diaphragms 23 and 24 when the latter are performing their function.

20 A U shaped bracket 55 extends from the rear face of the frame 32 and has extending therethrough the tension arm C with the hook end 56 and the threaded end 57. An adjusting nut 58 is in threaded engagement 25 with the threaded end 57 and the hook end 56 bears against the point 52^a of the screw 52. The function of the tension arm C is to preferably maintain the point 52^a of the screw 52 to the rear of the plane of diaphragms 23 and 24. When the bracket B is maintained in operative position with its projections 50 and 51 they are seated in their respective bearings 40 and 41 and the projections 33 are seated in their bearings 39.

30 By virtue of the contact between the point 52^a and the hook end 56 being to the rear of the bearings of the bracket B, a pulling effect is produced to properly tension the said bracket on its bearings.

40 The arm 48 has connected thereto a support 63 for the stylus 64.

To use the device as a sound reproducer and referring to Figs. 1 and 4 inclusive the stylus 64 is engaged with the sound record groove of a record disc R, which rotates with the usual turntable 140 of a talking machine. If the sound record groove is of the vertical type with up and down cuts, the stylus 64 has imparted thereto vertical oscillations. The stylus supporting bracket B communicates its movements to the supporting and oscillating plate A, which latter oscillates on the bearings 39. These oscillations are transmitted to the transverse arms 53 and 54, and thereby the diaphragms 23 and 24 are simultaneously vibrated in the same direction. The vibrations of the diaphragms produce sound waves which flow through the branch tone arms 27 and finally 55 through the tone arm 25 to the horn of a talking machine not indicated in the drawings.

The tension arm C maintains the plate A and the bracket B in tensional relation with each other and with the supporting frame

32. By means of the tensional relations of the said plate A, the bracket B and the frame 32, the diaphragms will be maintained in a neutral position without any strains when not vibrating. As soon as the diaphragms 23, 24 are vibrated by the coaction of the stylus 64 and the sound groove of the record and the related elements, each vibration of the diaphragms meets the tension of the elements referred to. When the sound record through the intervention of the stylus 64 and its coacting elements releases the strain on the diaphragms, the stored energy of the parts in tensional relation referred to assists in moving the diaphragms back to their initial neutral positions. The stylus 64 is maintained in balance by reason of the interposed connections between it and the two diaphragms 23 and 24.

It will be noted that if no tensional relation existed between the plate A, the bracket B and the frame 32, the weight of the sound boxes 20 and 21 and their related elements would force down the bracket B with its related elements toward the record disc R, and by reason thereof a bending movement would be established in the bracket B, by reason of which the diaphragms would be strained and forced inwardly. The tensioning of the elements A, B and the frame 32 compensate this tendency and maintains the diaphragms in their normal and neutral position.

In case a record disc with lateral undulations is used in place of the disc R, the bracket B will be oscillated on the vertical bearings 40, 41, and the transverse arms 53, 54 will be alternately oscillated, by means of which the diaphragms will be alternately vibrated. That is to say, when one diaphragm is moving inwardly the other one is moving outwardly.

Referring to Figs. 7 and 8 the invention is modified by substituting for the bracket B the ring 66, which latter has formed therewith the bifurcated projection 67, that is detachably fastened to the transverse arms 53 and 54. A fulcrum pin 68 extends from the upper portion of the inner face of the ring 66. A screw 69 with the bearing point 70 is in threaded engagement with the lower portion of the ring 66. A pair of fulcrum pins 72 extend from the frame 32 and support the central portion 73, which in turn engages the pin 68 and the point 70 of the screw 69. An arm 75 extends from the ring 66, and a stylus support 76 for the stylus 77 extends from the arm 75.

In the modification indicated in Figs. 7 and 8, the operation is essentially the same as described and in playing a vertical cut record portion 73 will oscillate on the pins 72, and through the transverse arms 53 and 54 will impart to the diaphragms 23 and 24

simultaneous vibrations in the same direction. When using a lateral cut record the ring 66 will oscillate on the pin 68 and the bearing point 70 and there will be imparted to the diaphragm vibrations in opposite directions.

In the operations of the invention it has been described as a sound reproducer, and it is evident that when sound waves are transmitted to the diaphragms of the device that the stylus thereof can function as recorder.

It must be understood that the invention as described and shown is only illustrative thereof and is not to be considered limitative, as various modifications may be made thereof without departing from its spirit.

Having described my invention what I desire to secure by Letters Patent and claim is:

- 20 1. In a device of the character described, the combination of a pair of sound boxes, a diaphragm for each sound box, a stylus supporting bracket coacting with the diaphragms, a stylus for the said supporting bracket, the latter when coacting with a vertical cut record vibrating both diaphragms in the same direction and when coacting with a lateral cut record vibrating the diaphragms in opposite directions.
- 25 2. In a device of the character described the combination of a pair of sound boxes, a diaphragm for each sound box, a single stylus supporting bracket for both diaphragms and connected thereto and mounted to oscillate about axes at right angles to each other and tensioned by its connection with the diaphragms and a stylus for said supporting bracket.
- 30 3. In a device of the character described the combination of a pair of sound boxes, a diaphragm for each sound box, a single stylus supporting bracket for both dia-

phragms mounted to oscillate about axes at right angles to each other and tensioned by its coaction with the diaphragms, said supporting bracket for both axes vibrating in planes at right angles to the diaphragms and a stylus for said supporting bracket.

4. In a device of the character described the combination of a pair of sound boxes, a diaphragm for each sound box, said diaphragms in the same plane, a single stylus supporting bracket for both diaphragms mounted to oscillate about a pair of axes at right angles to each other and tensioned by its coaction with the diaphragms and a stylus for said supporting bracket, said supporting bracket moving in planes at right angles to the diaphragms, both when said stylus is coacting with a vertical cut record and also when coacting with a lateral cut record.

5. In a device of the character described the combination of a pair of sound boxes, a diaphragm for each sound box and in the same plane, a supporting and oscillating plate supported to oscillate in a plane at right angles to the plane of the diaphragms, a stylus supporting bracket adapted to oscillate on said plate with its axis of oscillation at right angles to the axis of oscillation of said plate, said supporting bracket connected to said diaphragms and tensioned by its coaction therewith, a stylus extending from said bracket, said bracket moving in planes at right angles to the diaphragms when said stylus is coacting with a vertical cut record and also when coacting with a lateral cut record.

Signed at the borough of Manhattan, city of New York, in the county of New York and State of New York, this 1st day of October A. D. 1921.

ANDRÉ JUNOD.
